No. 866,774.

PATENTED SEPT. 24, 1907.

L. CASPER.

MACHINE FOR PASTING AND ATTACHING LABELS.

APPLICATION FILED JAN. 29, 1906.

UNITED STATES PATENT OFFICE.

LOUIS CASPER, OF CHICAGO, ILLINOIS.

MACHINE FOR PASTING AND ATTACHING LABELS.

No. 866,774.

Specification of Letters Patent.

Patented Sept. 24, 1907.

Application filed January 29, 1906, Serial No. 298,535.

To all whom it may concern:

Be it known that I, LOUIS CASPER, of Chicago, in the county of Cook and State of Illinois, have invented a new and useful and Improved Machine for Pasting and Attaching Labels, of which the following is a description, reference being had to the accompanying drawings, forming a part of this specification, in which corresponding letters of reference in the different figures indicate like parts.

10 The object of my invention is to so construct a machine for pasting and attaching labels to packages for shipment or otherwise, that the label may be passed automatically into contact with a paste supplying element whereby paste or other adhesive material 15 may be applied thereto and the label, after being so pasted upon one side, may be caused to adhere to the object to which it is intended to be attached.

To these ends, my invention consists in the combination of elements hereinafter more particularly described and definitely pointed out in the claims.

Figure 1, is a plan view of a device embodying the features of my invention, Fig. 2, is a vertical sectional view taken upon the line 2—, Fig. 1, viewed in the direction of the arrow there shown, Fig. 3, is an enlarged sectional view in detail taken upon the line 3—, Fig. 1, viewed in the direction of the arrow there shown, Fig. 4, is a vertical sectional view taken upon the line 4—, Fig. 1, viewed as indicated by the arrow therein, and Fig. 5, is a front view of the paste-reservoir.

Referring to the drawings, 1 indicates a cross-bar, to the ends of which is connected by means of screws 2, 2, parallel arms 3, 3, the whole forming a frame work to which is rigidly attached a rearwardly extended shank and handle 4. To the forward ends of the arms 3 and extending between the two, is attached a sheet-metal paste-reservoir 5, within which is located a paste roller 6, having end journals 7, 7, which are fitted in suitable bearings in the ends of 35 the arms 3. The roller 6 projects above and slightly in the rear of the paste receptacle, the rear wall 8 of which is cut away as shown in Figs. 2 and 4, for this purpose. A sliding sheet metal plate 9, Figs. 1, 2 and 5, having inturned flanges 10, 10, adapted to engage corresponding grooves in the ends of the paste receptacle, is secured by means of said flanges and grooves to the top of said receptacle, said plate being free to slide back and forth in said grooves so that it may be adjusted with reference to the roller 6 to form 50 a scraper for the purpose of regulating the amount of paste to be delivered by the roller as hereinafter stated.

Arranged parallel with the roller 6 is a shaft 11 having end bearings in the arms 3, 3, said shaft being preferably provided with collars 12, 12 to prevent 55 endwise movement. Mounted upon the shaft 11, is one or more but preferably a plurality of wheels 13,

the number of which may be varied indefinitely according to the size of the machine and the character and width of the labels to be used therewith, said wheel or wheels being knurled upon the periphery. 60

The journals of the shaft 11 are mounted in elongated bearings 14, one of which is shown in Fig. 4, so as to permit a slight forward and backward play of said shaft in the frame. Tapped into the cross-bar 1 in alignment with the handle 4, is a screw-threaded rod 65 15, which rod extends forward in the plane of the shaft 11. Said rod is provided with a bore 16, Fig. 3, into which is loosely inserted a pin 17, having a head thereon to which is attached a forked bearing-piece 18, arranged to bear against the shaft 11. A coiled spring 19 is mounted upon the part 15 and has one end arranged to bear against the head of said pin and the other against an adjusting nut 20 upon the rod 15 whereby the tension of the spring may be adjusted. The pressure of said spring serves to push the shaft 75 21 forward so that the wheels 13 will be caused to press against the periphery of the roller 6 with sufficient force to turn the latter when the machine is moved forward upon the wheels 13. This action causes the roller 6 to rotate in the direction of the arrow and to 80 convey the paste 21 upon its surface towards the wheels 13.

In order to prevent a reverse action of the paste roller so as to cause the paste to be piled up upon top of the plate 9, I attach a ratchet-wheel 22 to the shaft 85 11 which is engaged by means of a spring-actuated pawl 23 attached to the frame.

A smoothing roller 24 is journaled upon the horizontal portion of a wire 25, Figs. 1, 2 and 4, the ends of which are bent upwardly and secured in vertical bores 90 at the rear ends of the parts 3.

A sheet-metal guard, generally designated by 26, is attached at its ends to the frame, said guard having a horizontal portion 27 and an inclined portion 28, which latter extends downwardly into the bight between the 95 roller 6 and the wheels 13. The object of this guard, which is also a guide, is to so direct the label 29 as it is fed between the paste roller and wheels, that the entering wedge thereof shall not be directed into the paste box or against the rear wall thereof.

The operation of said device is as follows: The handle of the device being grasped by one hand, a label, with the printed side uppermost, is inserted beneath the guard with its lower edge in the bight between the paste roller and the wheels. The latter being pressed 105 by the action of the spring 19 against the paste roller, causes the roller to rotate as the machine is pushed forward, with the wheels bearing upon the object to which the label is to be attached. This action serves to draw the label in between the wheels and paste 110 roller, and to direct it downwardly until the under face, upon which paste is evenly distributed by means

of the paste roller, is brought into contact with the package, whereupon the wheels leave that part of the package upon which they are first pressed and roll directly upon and over the label. A continuation of 5 the movement will cause the smoothing roller to press the entire surface of the label against the surface to which it is to be attached. As soon as the advance edge of the label is brought into contact with the surface to receive it or before the opposite edge shall have 10 passed from the paste roll, the device should be tilted so as to lift the wheels from the surface of the label and cause all the pressure to bear upon the smoothing roll. As soon as the upper end of the label leaves the paste 15 roller the latter ceases to rotate provided the device is tilted as stated. This will prevent the wheels from rotating while in direct contact with the paste roll, thus preventing them from receiving paste upon their peripheries, which might cause the outer face of the next label to be slightly smeared with paste. A little 20 practice will soon enable an operator to use the device with speed and certainty, and without danger of distributing paste in the wrong place.

By adjusting the plate 9 the thickness of the film of paste upon the roller may readily be determined. 25 If long narrow labels are to be used it is obvious that a single wheel instead of a plurality may be used; and, while I prefer to make the periphery thereof narrow as shown its width may be varied indefinitely.

Having thus described my invention, I claim:

30 1. A device for applying paste to labels and attaching the latter to surfaces, in which is combined a source of paste supply, a paste roller arranged to receive paste therefrom and revolute means held under resilient pressure behind said roller for primarily engaging therewith 35 as well as with the surface to which the label is to be

attached, to cause the label to first move between said paste roller and said revolute means and thence upon said surface beneath said revolute means.

2. A device for applying paste to labels and attaching said labels to surfaces, consisting of a paste receptacle, a 40 paste roller arranged to partially enter therein, revolute means in spring controlled engagement with said paste roller for primarily engaging therewith as well as with the surface upon which the label is to be attached to cause the label to move between said paste roller and said revolute means and thence upon the surface beneath said revolute means, and a smoothing roller behind said revolute means.

3. A device for applying paste to labels and attaching said labels to surfaces, consisting of a paste receptacle, a 45 paste roller arranged to partially enter therein, a shaft parallel with said paste roller having a series of wheels thereon in normal contact with the periphery of said paste roller, and a spring for yieldingly pressing said wheels into normal contact with the periphery of said 50 roller, whereby upon introducing the edge of a label between said roller and said wheels and rotating the latter in frictional contact with the surface to which the label is to be attached, said label may be caused to move between said roller and wheels and thence upon said surface beneath said wheels.

4. A device for applying paste to labels and attaching said labels to surfaces, consisting of a paste receptacle, a paste roller arranged to partially enter therein, a series of wheels arranged to engage the periphery of said paste 55 roller, means for yieldingly pressing the same against said roller and means in the right between said roller and wheels for directing the label rearwardly as the same is moved downwardly, after having passed between said roller and wheels.

In testimony whereof, I have signed this specification in the presence of two subscribing witnesses, this 27th day of January, 1906.

LOUIS CASPER.
